US00D661312S

(12) **United States Design Patent**
Vance et al.

(10) **Patent No.:** **US D661,312 S**
(45) **Date of Patent:** **** Jun. 5, 2012**

(54) **DISPLAY SCREEN PORTION WITH USER INTERFACE**

(75) Inventors: **Michael Steffen Vance**, Kenmore, WA (US); **Jasdeep Singh Chugh**, Renton, WA (US); **Feridoon Malekzadeh**, Seattle, WA (US); **Valerie Lynn Goulart**, Seattle, WA (US); **Jupiter Macleod Barton**, Seattle, WA (US); **Jared T. Benson**, Pleasant Hill, CA (US); **Christian Robertson**, Concord, CA (US); **Shilpa R. Shah**, Oakland, CA (US); **Gabriel J. White**, San Francisco, CA (US)

(73) Assignee: **T-Mobile USA, Inc.**, Bellevue, WA (US)

(**) Term: **14 Years**

(21) Appl. No.: **29/384,637**

(22) Filed: **Feb. 1, 2011**

Related U.S. Application Data

(63) Continuation of application No. 29/334,510, filed on Mar. 27, 2009, now Pat. No. Des. 631,891.

(51) **LOC (9) Cl.** **32-00**

(52) **U.S. Cl.** **D14/486**

(58) **Field of Classification Search** D14/485-495; 715/700-867

See application file for complete search history.

(57) **CLAIM**

The ornamental design for a display screen portion with user interface, as shown and described.

DESCRIPTION

FIG. 1 is a front view of a user interface for a portion of a display screen showing the claimed design; and,

FIG. 2 is a front view of a user interface for a portion of a display screen showing the claimed design in accordance with a second embodiment.

The portion of the display screen and the portions of the user interface illustrated in broken lines form no part of the claimed design.

1 Claim, 1 Drawing Sheet
